UNITED STATES PATENT OFFICE.

EVERETT T. PACKARD, OF AVON, MASSACHUSETTS.

LUG-STRAP.

1,305,402.

Specification of Letters Patent. Patented June 3, 1919.

Application filed September 5, 1918. Serial No. 252,702.

To all whom it may concern:

Be it known that I, EVERETT T. PACKARD, a citizen of the United States, residing at Avon, in the county of Suffolk, in the State 5 of Massachusetts, have invented a certain new and useful Improvement in Lug-Straps, of which the following is a specification, reference being had to the accompanying drawings.

10 This invention relates to lug straps for use with picker sticks of broad looms, my object being to provide a specially serviceable form of lug straps and, with that end in view, I have provided the device illustrated in the annexed drawings, in which the Figure 1 is a side elevation of a lug strap embodying my present improvements, showing also a portion of the coöperating picker stick, and Fig. 2 is a top or plan view 15 of the same parts. Fig. 3 is a central, longitudinal, sectional, view of the lug strap taken on the line 3—3 of Fig. 3, and Fig. 4 is a horizontal, sectional, view taken at the point 4—4 of said Fig. 3. Fig. 5 is a 20 detached, top view of a slightly modified construction of the lug strap, and Fig. 6 is a horizontal, sectional, view taken on the line 6—6 of Fig. 7; said Fig. 7 being a side elevation of said lug strap.

25 Referring now to these drawings, the letter *a* indicates a portion of a picker stick of the usual, or any other approved, construction and *b* denotes the customary sweep stick to which the lug strap is secured by 30 means of bolts *c*—*c*.

The lug strap, as here shown includes an outer strap *d* of sheet metal which is doubled upon itself to provide a curved end portion *d'*, in which is seated a buffer block 35 *e*, also plates *f*—*f* formed preferably of wood, which are located, in opposition to each other, on the inner faces of the strap *d*; the said plates being of such length that their inner ends abut the buffer *e* and thus 40 prevent said buffer from working forward; that is to say, away from its seat in the curved end portion *d'* of the metal strap. The buffer *e* is formed preferably of a composition which consists in part of rubber 45 and which is slightly resilient so as to cushion to some extent the rigid shock which

would otherwise result from the impact of the picker stick with said buffer.

By preference the inner face of the buffer is formed at its mid portion with a curved 55 or rounded face *e'* where it engages the picker stick and at the opposite sides of said curved portion the buffer may be cut away vertically, as at *e*² Fig. 6, to receive the squared ends of the side plates *f*—*f*. In the 60 buffer shown in Figs. 1, 2, 3 and 4 the curved portion of the buffer extends from side to side of the buffer and the engaging ends of the said plates *f*—*f* are correspondingly curved to fit the same. By preference the 65 wooden side-plates *f*—*f* are riveted to the metal strap *d* as is best seen at *g*—*g* in Figs. 4 and 6.

In order to support the lug strap in the proper position with respect to the picker 70 stick, I may provide in the buffer an eye-bolt *h* which is adapted to receive a strap *i* whose upper end is fastened to the picker stick in the usual manner and, for the purpose of preventing the accidental disarrangement of the buffer *e*, I pass a cotter pin *k* through said buffer and through the metal strap *d*, in the form of lug strap shown in Figs. 5, 6 and 7 but in the construction 75 illustrated in Figs. 1, 2, 3 and 4 the cotter pin is not necessary, as the curved ends of the side plates *f*—*f* serve to prevent such disarrangement.

I find by continued practical use that the composition buffer *e* will wear satisfactorily 80 for a much longer period of time than the leather or raw-hide buffers now commonly used. When, however, it becomes necessary to remove a worn-out buffer and replace it with a new one, it may be readily done in 85 the strap of Figs. 5, 6 and 7 by removing the cotter pin *k* and sliding the buffer upward, or downward, until it leaves the strap *d* whereas in the structure of Figs. 1, 2, 3 and 4 it is necessary to remove the strap 90 from the sweep stick and spring the sides of said strap apart in order to remove the worn buffer and to replace it with a new one.

Having thus described my invention, I 95 claim:

1. The improved picker stick consisting of

an outlining strap doubled upon itself, a buffer seated in the doubled end portion of said strap and opposing plates located in said strap; the ends of said plates abutting 5 the buffer.

2. The improved picker stick consisting of an outlining sheet metal strap doubled upon

itself, a resilient buffer seated in the doubled end portion of said strap, opposing plates located in said strap and abutting the said 10 buffer, and means for preventing the vertical movement of the buffer in said strap.

EVERETT T. PACKARD.
